UNITED STATES PATENT OFFICE.

SYLVAN MILTON STRAUS, OF GLOVERSVILLE, NEW YORK, ASSIGNOR TO GLOVERSVILLE WELT CO., INC., OF GLOVERSVILLE, NEW YORK.

PROCESS FOR PRODUCING LEATHER WELTS.

No Drawing.

Application filed January 25, 1926. Serial No. 83,770.

This invention relates to a process or method for producing flat strips of leather of uniform width, with straight edges, and of a length many times as great as the 5 length of the skins from which the same is made.

In the manufacture of gloves and other articles made of leather a welt is used, this being a narrow strip of leather adapted to 10 be introduced into the work, sometimes through guides that are a part of the equipment of the sewing machine and the passageways through which are such that a 15 welt strip of more than a given thickness, or one the edges whereof are not parallel and straight, cannot pass therethrough. It is usually desirable to limit the thickness of the welt strip, although in the 20 manufacture of the cheaper grades of gloves and the like but little attention is paid to the thickness of the welt.

Similar strips, but of somewhat greater width are also used for bindings in the manufacture of certain leather and canvas goods, 25 and these binding strips are often to have their edges folded by passing them through a folding device. When the strips are to be used for bindings it is very desirable that the thickness thereof be limited to an allowable 30 maximum.

As skins vary in thickness, and the thickness of each skin varies at different points therein, and a welt strip if made of two pieces joined together will naturally be 35 thicker at the point of joining, it has heretofore been impracticable in the production of the finer grade of gloves to make use of welt strips having a length which was greater than that of the skin from which it 40 was cut, on account of the impracticability of cementing the short lengths end to end without producing more than the allowable maximum thickness at the joints and of maintaining absolute parallelism of the 45 edges of the different joined parts which make up the spliced welt, by keeping the edges of the joined parts in perfect alignment.

This invention has for its object the production of flat, comparatively narrow, 50 straight strips of leather of uniform width, the thickness whereof is at all points limited to an allowable maximum, so as to insure the

free passage thereof through the guide when the welts are being used in the manufacture 55 of gloves, and through the folding devices when they are used as bindings on leather and canvas goods, such as sporting goods. This process is particularly applicable to the production of glove welts to be used in 60 the higher grades of work as it will materially reduce the cost of producing such welts in long lengths, and will at the same time insure a perfectly straight, smooth running and working welt; a welt very superior to 65 those heretofore produced, in that they are of more uniform thickness and the edges thereof are not only parallel to each other but are also straight throughout their entire 70 length.

Instead of initially cutting the skins into strips which are the width of the desired welt, and cementing the strips together end to end until the desired length is attained, necessarily depending on the natural thickness of the skins and the expertness of the workmen to keep the thickness of the strip within the allowable limit at the points where the pieces are joined together, and to maintain the edges of the joined pieces in 80 exact alignment, I employ a variation of the usual procedure, and introduce certain operations not heretofore used in the production of glove welts and the like. 75

The skins from which the strips are made, 85 usually sheep skins, are first subjected to a tacking process in order to firm them. The skins being sufficiently firmed, they are now cut into strips the width whereof is more than twice as great as the width of the welts 90 to be produced. This cutting may be done on any type of multiple disc leather cutting machine. The ends of these strips are next squared, this being done on any suitable shear having associated therewith guiding 95 means which will insure a square end; and the squared ends are then skived down to almost a feathered edge, opposite ends being preferably skived on opposite sides. The short strips so prepared are next cemented 100 together end to end, the skived ends lapping onto each other, until a strip of a desired length has been produced.

The strip is now preferably measured, by being run through a suitable measuring 105 mechanism, to insure its being of the proper

length; but the next step in my complete preferred process is the reduction in thickness of any part of the manufactured strip which may be in excess of the allowable maximum, either by reason of thick spots in the skin from which the parts thereof were cut or to the lapping of the parts at the points of joining, by scraping off a part of the skin at the points where such excess occurs, or removing the excess thickness in any practical manner. This is preferably accomplished by passing the manufactured strip through feed rolls designed to maintain a tension on the strip as it is passing therethrough, one of said rolls lying in such close proximity to a rotating abrasive wheel or roll that the distance between the surface of the abrasive roll and one of the feed rolls, over which the strip of skin is passing, is equal to the allowable maximum thickness of the welt being produced. The surface of the abrasive roll is caused to travel in the same direction as, but at a higher speed than is the strip of leather, thereby causing any thick parts of, or points in the strip to be worn down to the allowable maximum thickness.

The gaged strip of leather is next passed through a leather cutting machine which comprises a series of cutting knives or discs so spaced that the distance between adjacent cutters is equal to the width of the welt strips which are wanted. The width of the initially formed strip which is to be divided into welt widths is to be somewhat greater than the distance between the end cutters of the series; and it is to be so guided into the machine that a narrow waste strip will be cut from each edge thereof, thereby insuring absolutely true, straight, parallel edges on each of the long welt strips which this operation completes.

As these welts emerge from the cutting machine they are preferably passed through a reed which will separate them one from the other and direct each into its individual receiver. These welts may, however, be

delivered directly to machines adapted to wind them upon spools or bobbins.

I claim:

1. A method of producing long lengths of glove welts consisting in initially cutting firmed skins into strips the width whereof is such that a plural number of finished strips of the desired width may be cut therefrom and leave a remainder, squaring the ends of the initially cut strips and skiving the squared ends, cementing the skived square ended strips together end to end, reducing any overhick spots in the resulting fabricated strip to an allowable maximum, then simultaneously trimming both edges of the strip in straight parallel lines and slitting the remainder thereof into strips of the desired width. 65

2. A method of producing simultaneously a multiple number of long, narrow leather strips with straight parallel sides consisting of initially cutting skins into strips slightly wider than the sum of the widths of a plural number of the finished strips such as are to be produced, squaring then skiving the squared ends of said strips, cementing the skived square ended strips together end to end, then simultaneously trimming both edges of the resulting fabricated strip in straight parallel lines and slitting the remainder into strips of the desired width. 70

3. A method of producing simultaneously a multiple number of long, narrow leather strips with straight parallel sides consisting of initially cutting skins into strips slightly wider than the sum of the widths of a plural number of the finished strips such as are to be produced, skiving the ends of said strips, cementing them together end to end, then simultaneously trimming both edges of the resulting fabricated strip in straight parallel lines and slitting the remainder into strips of the desired widths. 85

In testimony whereof I have affixed my signature.

SYLVAN MILTON STRAUS.
